SHREDDER TYPE CULINARY ARTICLE

Max Hayman and Clarence W. Galen, Battle Creek, Mich., assignors to Gustave Heyman and Max Hayman, jointly, both of Battle Creek, Mich.

Application May 20, 1947, Serial No. 749,302

10 Claims. (Cl. 146—180)

1

The present invention relates broadly to a culinary article, and in its specific phases to a colander type shredder.

Slicing or shredding foods such as cabbage, potatoes, carrots, onions, cheese, et cetera, is a very common procedure carried on by both housewives and commercial cooks. To do this work several different types of manually operated shredders have been proposed with the bulk of them inherently subject to the danger of cutting the user's fingers which hold the item being shredded, and particularly so when that item becomes reduced in size. In certain instances special equipment has been developed to avoid this condition, for example, mechanical devices for holding a potato while slicing it to produce potato chips. The problem has been so difficult of solution that machine shredded kraut, coconut, cheese, fresh vegetables, et cetera, are regularly purchasable on the open market. One of the manually operated shredders which have been proposed, and which is particularly subject to cutting the operator's fingers, is of bowl shape with a pair of cutting blade panels mounted on opposite sides of the bowl. In using that assembly the bowl is placed upright to catch the slices or shreds produced while the operator passes the item to be cut up and down one of the cutting blade panels on the under side of the bowl where the position of the hand relative to the knives cannot be watched. It was a recognition of the problem involved, its inherent difficulties, and the shortcomings of the prior art, which led to the conception and development of the present invention.

Accordingly among the objects of the present invention is the provision of a shredder assembly which is shaped like a colander with a large open top, has inwardly tapering sides, and a relatively small base with rounded feet, said shredder having outwardly projecting cutters with their cutting edges up when the open end of the assembly is down.

Another object is to provide a shredder assembly having perforations in its sides and bottom in addition to side cutters, all of which act as drainage openings when same is mounted open side up and used as a colander.

Another object is to provide a shredder assembly with a plurality of relatively flat panels, each panel having a different size outwardly projecting cutter or cutters adapted for use with the assembly mounted on a suitable surface with its large open end down, a thing which aids in stabiliz-

ing the assembly as well as keeping the cutting operation under direct observation.

Another object is to provide a shredder assembly which has safety guides along side of each 5 of the cutter panels as an aid to protecting the user's fingers from injury on the cutting edges.

A further object is to provide a shredder assembly which in some constructions will have the cutting or shredding portions made in the form 10 of separate panels which may be either removable or permanently mounted in place on the body of the shredder assembly.

A further object is to provide a shredder assembly which may be completely made as a 15 stamping, or may have separate cutting or shredding panels either fastenable to a stamping or to a die casting of suitable metal or plastic.

A further object is to provide a combination 20 shredder and colander which is simple in construction and easy to use in safe manner.

Still further objects and advantages of the present invention will appear as the description proceeds.

To the accomplishment of the foregoing and 25 related ends, the invention, then, consists of the means hereinafter fully described and particularly pointed out in the claims, the annexed drawings and the following description setting forth in detail certain means for carrying out the invention, such disclosed means illustrating however, but several of various ways in which the principle of the invention may be used.

In the annexed drawings:

Figure 1 shows a perspective view of a preferred form of the shredder of the present invention with same in normal shredding position.

Figure 2 shows a view of the inside of the shredder assembly as seen from the bottom of Figure 1.

Figure 3 shows a fragmentary modified construction where separately formed panels carrying the cutting blades of the shredder are mountable on the shredder body in conventional manner.

Referring more particularly to Figure 1 of the 45 drawing, it will be noted that the present invention involves a tapered side body member 1 which preferably has a flange 2 at its top or open end, and rounded feet 3 at its bottom or lower end. In order to make the apparatus easier to handle, same may be provided with handles 4 and 5.

Body member 1 is provided with four substantially flat shredder panels 6, 7, 8, and 9. Shredder panel 6 has a single angularly mounted cutting blade 10, which is particularly adapted for 55 the shredding of cabbage or the slicing of pep-

pers, potatoes, or the like. Shredder panels 7, 8, and 9, on the other hand, have small, medium, and large individual cutters 11 in staggered row multiple groups suitable for narrow strip shredding or cutting of onions, carrots, cheese, coconut, or the like. The cutting edges 12 of these cutters are formed so that with the shredder assembly mounted open top down as shown in Figure 1, the cutting edges will be up and outwardly directed to facilitate shredding by downward passage of the item to be shredded, over the cutters 11, while under clear observation. The open top of the shredder assembly forms a large base for the shredder under conditions of use, thus stabilizing it against dangerous slipping accidents, and at the same time, the bottom or foot portion presents smoothly rounded surfaces which allow the operator to place one hand on same and thus hold the shredder substantially against movement under conditions of use.

Recognizing that injury to the user of a shredder is a common occurrence, the present shredder is provided with outwardly projecting safety guides 13 on opposite sides of each of the shredder panels. These raised safety guides are such that the user may conventionally hold in her fingers the article to be shredded, and yet keep her fingers steady and away from the cutting edges by sliding the heel, or even the edge, of her hand up and down one of these safety guides regardless of whether she is right handed or left handed. At the same time, this permits close observation of the shredding procedure at all times, and facilitates safe operation.

In preferred construction, the flare of the sides of the shredder body member together with cutters 11 and safety guides 13 is such that same may be formed as a stamping with the inner or male die freely removable therefrom. The final shredder assembly may be produced in various ways, of which perhaps one of the more convenient would be to first form a plain blank following which the shredder panels and safety guides could be formed, and perhaps lastly, the perforations could be made in the bottom of the shredder and substantially from safety guide rib to safety guide rib between panels. Where handles are used, same would be normally riveted or welded in place as one of the final operations. The cutting edges 12 of the shredders would also be sharpened in conventional manner and if desired, the whole assembly would be plated for appearance and rust resistance.

Instead of having the cutters 11 made as an integral part of the shredder body member, same may be made as part of separate panels 14, Figure 3, adapted to be mounted over openings 15 in body member 1. These panels may be made removable such as with interlocking members 16 and screws 17, or if desired these panels may be welded or riveted into place, or die cast in place as inserts where the body member 1 of the colander is made of either die cast metal or plastic, and it is intended that the showing in Figure 3 be considered as diagrammatically illustrating all of these various constructions.

While the present invention is primarily a shredder, it will be noted that by inverting same so that the open end is up, it becomes a colander wherein the perforations as well as the colander cutters form drainage openings thus meeting standard colander requirements.

Other modes of applying the principle of our invention may be employed instead of those explained, change being made as regards the article and combinations disclosed, provided the

means stated by any of the following claims or the equivalent of such stated means be employed.

We therefore particularly point out and distinctly claim as our invention:

5. 1. A culinary device of the character described, which comprises a tapered body member with an open upper end and a flat closed lower end, and at least one cutter panel on the side of said body member, said cutter panel having outwardly projecting cutter means, said cutter means having the cutting edge thereof directed away from the open end of the body member, said lower end having an unobstructed bottom surface adapted as a hand rest when said body is inverted.
10. 2. A culinary device of the character described, which comprises a tapered body member with an open upper end and a flat closed lower end, substantially flat cutter panels on the side of said body member, said cutter panels having at least one outwardly projecting cutter means, said cutter means having the cutting edge thereof directed away from the open end of the body member, said lower end having an unobstructed bottom surface adapted as a hand rest when said body is inverted, and guard ribs projecting outwardly from said panels at least as far as said cutter means and extending alongside said means.
15. 3. A combination shredder and colander apparatus, which comprises a perforated bowl shaped member having an open top and a flat closed bottom adapted for a hand rest when said member is inverted, at least one generally flat separate cutter panel, said body member having a suitable opening for said cutter panel, and means for fastening said cutter panel on said body member over said opening, said cutter panel having at least one outwardly projecting cutter means, said cutter means having the cutting edge thereof directed away from the open end of said body member when said cutter panel is fastened thereon, and guard ribs embossed outwardly from said body alongside said opening and projecting outwardly at least as far as said cutter means.
20. 4. A combination shredder and colander apparatus, which comprises a perforated bowl shaped member having an open top and a flat closed bottom adapted for a hand rest when said member is inverted, at least one separate cutter panel, said body member having a suitable opening for said cutter panel, means for fastening said cutter panel on said body member over said opening, said cutter panel having at least one outwardly projecting cutter means, said cutter means having the cutting edge thereof directed away from the open end of said body member when said cutter panel is fastened thereon, and outward projecting safety guide means along side of said cutter panel and extending in a direction from the top of said bowl shaped body toward the bottom thereof.
25. 5. A combination shredder and colander apparatus, which comprises a perforated bowl shaped body member with a relatively large open top and a closed bottom adapted on its underside as a hand rest when said member is inverted and having foot members projecting downwardly from the bottom thereof, a plurality of cutter panels on the side portion of said body member, each of said cutter panels having outwardly projecting cutter means, said cutter means having the cutting edge thereof directed away from the open top of the body member, and outwardly projecting safety guide ribs at the opposite side edges of at least one of said

cutter panels and extending in a direction from the top of said bowl shaped body toward the bottom thereof while projecting outward further than said cutters.

6. A combined shredder and colander comprising a single piece integral bowl-shaped body of sheet material, said body having four plane side panels disposed in downwardly converging relation and joined at their bottom by a flat perforate bottom panel approximating the size of the palm of a hand, said bottom having rounded foot elements pressed downwardly therefrom, rounded perforate corner panels joining the side edges of said side panels and extending to the tops thereof to form a continuous planar rim on said body, at least one of said side panels having shredding teeth stamped outwardly therefrom with the cutting edges of the teeth facing downwardly, and outwardly projecting smoothly rounded guard ribs pressed from said side panels and extending along each side of the teeth therein, said ribs projecting from said panels at least as far as the teeth project from the panel and terminating at their lower ends in tapered converging relation to the panels.

7. A combined shredder and colander comprising a single piece integral bowl-shaped body of sheet material, said body having a plurality of generally flat side panels disposed in downwardly converging relation and joined at their bottom by a perforate bottom panel approximating the size of the palm of a hand, said bottom having rounded foot elements pressed downwardly therefrom, rounded corner panels joining the side edges of said side panels and extending to the tops thereof to form a continuous planar rim on said body, said side panels having shredding teeth stamped outwardly therefrom with the cutting edges of the teeth facing downwardly, and outwardly projecting smoothly rounded guard ribs pressed from said side panels and extending along each side of the teeth therein, said ribs projecting from said panels at least as far as the teeth project from the panel and terminating at their lower ends in tapered converging relation to the panels.

8. A combined shredder and colander comprising an integral bowl-shaped body, said body having a plurality of generally flat side panels disposed in downwardly converging relation and joined at their bottom by a bottom panel having an unobstructed lower surface adapted as a hand rest when said body is inverted, said bottom having rounded foot elements pressed downwardly therefrom, rounded perforate corner panels joining the side edges of said side panels in approximately tangential fashion and ex-

tending to the tops thereof to form a continuous planar rim on said body, said side panels having shredding teeth projecting outwardly therefrom with the cutting edges of the teeth facing downwardly, and outwardly projecting smoothly rounded guard ribs projecting from said side panels and extending along each side of the teeth therein, said ribs projecting from said panels at least as far as the teeth project from the panel.

9. A combined shredder and colander comprising an integral bowl-shaped body, said body having a plurality of generally flat side panels disposed in downwardly converging relation and joined at their bottom by a bottom panel having an unobstructed lower surface adapted as a hand rest when said body is inverted, rounded corner panels joining the side edges of said side panels and extending to the tops thereof to form a continuous planar rim on said body, said side panels having shredding teeth projecting outwardly therefrom, and outwardly projecting smoothly rounded guard ribs projecting from said side panels and extending along each side of the teeth therein, said ribs projecting from said panels at least as far as the teeth project from the panel.

10. A combined shredder and colander comprising an integral bowl-shaped body, said body having a plurality of generally flat side panels disposed in downwardly converging relation and joined at their bottom by a bottom panel having an unobstructed lower surface adapted as a hand rest when said body is inverted, rounded corner panels joining the side edges of said side panels, said side panels having shredding teeth projecting outwardly therefrom, and outwardly projecting smoothly rounded guard ribs projecting from said panels at least as far as the teeth project from the panel.
